Primary Examiner — Darlington Ly

(74) *Attorney, Agent, or Firm* — Michael Best & Friedrich LLP

(57) **CLAIM**

The ornamental design for a motorcycle with saddlebags as shown and described.

DESCRIPTION

FIG. 1 is a front and left side perspective view of a motorcycle with saddlebags showing our new design; FIG. 2 is a front and right side perspective view thereof; FIG. 3 is a rear and left perspective view thereof; FIG. 4 is a right side elevation view thereof; FIG. 5 is a left side elevation view thereof; FIG. 6 is a front elevation view thereof; FIG. 7 is a rear elevation view thereof; FIG. 8 is a top plan view thereof; and, FIG. 9 is a bottom plan view thereof.

The broken lines are included for the purpose of showing portions of the motorcycle with saddlebags that form no part of the claimed design.

1 Claim, 9 Drawing Sheets
